UNITED STATES PATENT OFFICE

MARIE WILLIAM KRAUTH, OF HAMILTON, OHIO, ASSIGNOR TO KRAUTH & BENNING-HOFEN, OF HAMILTON, OHIO

AUTOGRAPHIC REGISTER

Application filed October 20, 1928. Serial No. 313,918.

This invention relates to improvements in autographic registers or manifolding machines, particularly for manifolding and dispensing shipping or sales bills, and the like.

5 In such types of machines the shipping or sales bills, as form lengths, are represented as strips of paper, either reel wound or folded into a packet, and dispensed in definite measured proportions corresponding to the individual shipping or sales bills lengths and severed from the strips.

For manifolding upon the several strips of a group, manifolding or carbon paper is placed between the several strips generally 15 for the portion over a writing table. The frictional pull of the strips when advanced or moved over the stationary carbon paper and across the free edge thereof, tends to curl or injure the edge.

20 It is, therefore, an object of the invention to provide a shield for the strip receiving edge of the carbon paper, and in the provision of a shield composed of pliable leaves engaged over the edge andlapping the opposite sides of the carbon paper.

Another object of the invention is to deposit a record strip, as fed or drawn over a writing table and taken from a supply packet, the supply packet formed by zigzag folding of 30 the strip, into a storage compartment of the machine and repacketed, the refolding accomplished automatically with the feeding advance of the strip, and to have the two packets as prefolded and refolded lie immediately 35 longitudinally adjacent one another within the body or casing of the machine below the strip feeding mechanism and writing table and preferably in separate compartments therefor. The strip is unfolded from one

40 packet and refolded into another packet in an orderly manner at any rate of speed under which the strip may be fed. The arrangement provides for compactness, offers freedom in the movement of the strip in unfolding and refolding and the packets are easily 45 accessible for insertion or removal.

Other objects and features of the invention will be more fully set forth in the description of the accompanying drawings, in which:

50 Figure 1 is a top plan view of an auto-

graphic register containing the present improvement, with the lid or marginal frame removed.

Figure 2 is a vertical section of the machine on line 2—2, Figure 1.

Figure 3 is a horizontal section on line 3—3, Figure 2.

Figure 4 is a detailed perspective view of the inside of the top cover for the storage compartment of the register at the front end of the machine, illustrating the guard plate for directing the record copy into the storage compartment, refolding the paper in packet form as substantially received from the supply packet.

Figure 5 is a detail perspective view of the devices for protecting one edge of the manifolding or carbon paper at the rear end of the writing table.

The machine is primarily adapted for feeding and dispensing form lengths of paper as shipping or sales bills in manifolding service, wherein a plurality of record strips or webs are disposed in superposed arrangement upon a writing table, each strip having feed arresting apertures, the apertures of the different strips being of such arrangement as to register with each other in successive longitudinally related sets, and are advanced over the writing table and dispensed by feed rollers or other mechanical feeding mechanism in definite measured lengths governed by said aperture spacing.

The feed or advance is suspended when the feeding mechanism is in cooperation with a set of apertures, requiring a manual restarting for a successive feeding and dispensing operation.

In the present disclosure, the feeding mechanism is of the roller type, comprising an upper roll 1 depressingly journalled at its opposite ends in the side frames 2—2 of the machine, the roll having peripheral contact with a pair of annuli or disks 3—3 fixed upon a shaft 4 journalled in fixed bearings in the side frames 2—2. The roll 1 and shaft 4 are in transmission connection by gearing.

The disks 3—3 occupy a spaced relation corresponding to the crosswise spacing of a set of apertures in the web, so that when the

5 apertures in the advancing movement of the strip reach the disks, the advance is automatically suspended. The apertures interrupt the feeding or bearing contact of the feed rolls with the paper and, therefore, are ineffective to transmit the paper with their rotation.

10 This operation applies to all of the strips employed in a manifolding group, irrespective of their number, whenever the arresting apertures of the several strips are brought in 15 registry with the feeding rolls. Thus, the several strips can be advanced in differential lengths, depending upon the relative longitudinal spacing of the apertures, but all brought to rest when in registry and in cooperation with the feed rolls.

20 For a successive advance, manually controlled or tripped starting mechanism is brought into action for advancing the strips sufficiently to dispel the apertures from the 25 feed arresting relation with the feed rolls and again bring the feeding rolls into contact with the paper, whereupon they again take hold and transmit the paper until a successive set of apertures in the strips are reached.

30 In conjunction with the annuli, pin devices are employed, mounted upon a shaft 5 to engage through the registering apertures in cooperation with the annuli to positively 35 withhold the strips against advance or displacement, and also to serve to bring the strips and form printing into registration and alignment. The pin devices are operated through and with the control of the starting mechanism, so that the pins are withdrawn initially to the starting of the strips and ready to engage into a successive set of apertures.

40 Full detail of construction of the starting mechanism and pin devices is not shown herein as these features are embodied in commercial machines well-known in the art, and do not form a part of the present invention.

45 For manifolding service, sheets or webs of carbon or manifolding paper 6 are disposed between the several form containing strips 8 of a group, and primarily for the area thereof lying to the writing table, and following the common practice in this art for furnishing a manifolding paper supply service for the number required for a group of form strips employed in the machine, the manifolding paper is reel wound into a multi-web roll and deposited within a tray or receptacle 55 holder disposed at one side of the machine and longitudinally thereof. In the present instance the holder is attached or integrally combined with a writing table 10, as a sheet metal plate, extending across the top of the 60 machine, and at its rear end hinged to the side frames adapting the table to be swung upwardly for convenience in threading or loading the machine.

65 The several sheets or webs of carbon paper extend crosswise over the writing table and

between the several form strips, and clamped in position by a flanged longitudinal edge of a margin frame 11 hinged at its rear end to the side frames and lying over the writing table, the margin frame providing a cover 70 for the rear portion of the machine.

To prevent the rear edges of the carbon paper to curl or become injured during the feeding motion of the form strips as they move across the edge of and onto the carbon 75 paper, shields 12 of a pliable material are lapped over the edges of the carbon paper marginally covering both upper and under sides thereof approximately for the full 80 width of the form strips, protecting the edges of the carbon paper and guiding the form strips over the carbon paper.

These shields are preferably formed of a pliable metal, as soft brass sheets, cloth-celluloid and others, looped around a cross rod 85 13 to provide a pair of extending leaves between which the rear edge of a carbon sheet is disposed. The rods 13 also serve as guides for the form strips over which they loop in extending from the supply source housed within 90 the body or compartment of the machine below the writing table and margin frame. A guide rod 13 is employed for each strip of the group so that each is individually guided over the rear end of the writing table as the strips are drawn from the supply compartment.

95 As shown, the guide rods or shield supports are mounted at their opposite ends within bars 14—14 respectively fixed to the underside of the writing table. The guard leaves in being looped over the supporting rods are free to swing thereon, facilitating 100 in loading the machine.

105 The strip supply is arranged in packet or pad form, comprising a plurality of record strips folded zigzag, the folds of one inter-engaged with those of the other, so as to divide superposed sets of superposed leaves 110 connected end to end. The strips at the lines folded are weakened to facilitate in packeting, and provide a squared edge pad or package and also serve for conveniently refolding and packeting, automatically within the 115 machine, one or more of the strips after manifolding, which are not dispensed from the machine.

120 In the present machine, the supply and refolded packets are compactly housed within respective compartments in the body of the machine immediately adjacent one another and in longitudinal order, rendering the packets easily accessible with the refolded packet approximately centrally below the feeding rolls, facilitating the refolding progressively with the feed of the strip into the storage compartment and irrespective of the speed 125 at which it is fed.

130 Both packets are inserted or removed from the top of the machine, the supply packet be-

ing deposited in the supply compartment 15 at the rear half of the machine by raising the margin frame and writing table and the re-folded record packet removed from the compartment 16 at the forward half of the machine by raising the sectional cover 17 covering the top of the machine forward of the feed rolls.

The strips in group from the supply packet 18 are threaded over a guide rod 19, the rod having its opposite ends supported in the side frames and located forward of the end of the supply compartment, so that one set of leaves, representing the portion between the folds, is completely withdrawn to the end of the fold before any pull is exerted to the successive set of leaves.

From thence the strips pass relatively over their respective guide rods 13 to and over the writing table and between the feed rolls, with the record strip threaded downwardly as it leaves the feed rolls over a guide rod 20 having its opposite ends secured in the side frames and beneath a curved guard 21 depending from the rear section 22 of the sectional cover 17, the guard directing the strip into the storage compartment 16 in a manner at which the strip is refolded along the weakened lines of the fold and in the packet form irrespective of the speed at which the strips are advanced.

Having described my invention, I claim:

1. In a machine of the character disclosed, a casing including a writing table for supporting a plurality of record strips in superposed relation, with manifolding paper disposed between the strips, the manifolding paper held stationary and the record strips for dispensing drawn longitudinally over the table across the manifolding paper, a shield 40 marginally covering an edge of the manifolding paper at the approaching side with respect to the direction of strip motion and crosswise thereof, the shield comprising a sheet of pliable material looped to provide a 45 pair of leaves for marginally engaging about an edge of manifolding paper, and a stationary cross rod mounted in said casing engaged between the leaves of said shield hingedly supporting the shield.

2. In a register: a casing provided with a packet-compartment; a platen supported by said casing over which paper-webs are drawn from the packet; a source of carbon-strip supply at one side of the casing from which transverse carbon-strips may be drawn; and a transverse guide over which the paper-webs pass from the packet to the platen, said guide being equipped with an apron extending therefrom adapted to overlap and protect the edge-portion of an underlying carbon-strip.

3. In a register: a casing equipped with a platen; a source of supply for paper-webs within said casing; transverse guides interposed between the source of supply and the

platen and equipped with aprons; and a carbon-strip supply mounted at one side of the casing from which carbon-strips may extend across the platen, the end-portions of said aprons serving to engage and protect the adjacent edge-portions of said carbon-strips.

4. In a register: a casing provided with a packet compartment; a platen supported by said casing over which paper-webs are drawn from the packet; a source of carbon-strip supply at one side of the casing from which transverse carbon-strips may be drawn; a transverse guide over which paper-webs pass from the packet to the platen; and a pair of apron members adapted to underlie and overlie the marginal portion of the carbon strip.

In witness whereof, I hereunto subscribe my name.

MARIE WILLIAM KRAUTH.
